12 Claims. (Cl. 226—71)

1

This invention relates to packaging machines of the type used for placing a measured quantity of material into a package and compressing the contents of the package.

One of the objects of this invention is to provide a machine of this type of improved and simplified construction and which is efficient and reliable in operation. Another object of this invention is to provide a method and a machine of this kind with means of improved construction for effecting the compressing of the material in a package. A further object is to provide a machine of this kind with packaging forms of improved construction in which the contents of the package are compressed, and from which the package with the compressed contents may be readily removed. A further object is to provide a machine of this kind with means of improved construction for ejecting the packages from the machine.

It is also an object of this invention to provide a machine of this kind in which the movement of the packing plunger acting on one package releases material for deposit in another package. It is also an object of this invention to provide means whereby the packing plunger while compressing the contents in one package also effects the discharge of another package from its packing form.

Other objects of this invention will appear from the following description and claims.

In the accompanying drawings which illustrate by way of example one embodiment of this invention:

Fig. 1 is a front elevational view of my improved machine.

Fig. 2 is an enlarged detail view of the filling tubes and other parts of the filling tube assembly shown in Fig. 1.

Fig. 3 is an enlarged front view of the packer plunger assembly shown in Fig. 1.

Fig. 4 is a vertical sectional view of the assembly appearing in Fig. 3, the plane of the section being substantially along the line 4—4 of Fig. 5.

Fig. 5 is a transverse sectional view of the assembly shown in Figs. 3 and 4.

Fig. 6 is an enlarged detail view of a portion of the drive mechanism provided for operating the moving parts of said machine.

Fig. 7 is a vertical sectional view of the packing form assembly shown in Fig. 1, the plane of the section being substantially along the line 7—7 of Fig. 8.

Fig. 8 is a top plan view of the packing form assembly shown in Fig. 7.

2

Fig. 9 is a view partly in plan and partly in horizontal section of a modified mechanism for operating the pusher plates which serve to discharge the filled bags onto a suitable conveyor.

Fig. 10 is a sectional view taken along the line 10—10 of Fig. 9.

As shown in the drawings, my improved machine comprises a weighing mechanism 5, a filling tube assembly 6, a packing plunger assembly 7 and a packing form assembly 8.

The weighing mechanism and its operating means

This mechanism comprises a feed chute 10, an automatic weighing scale 11, and a hopper 12. The scale 11 is provided with conventional automatic tripping means (not shown) which is actuated by the tripping shaft 13. When the machine is in use shaft 13 is intermittently operated

so that an accurate measured charge of the material delivered to weighing scale 11 by feed chute 10 is deposited in hopper 12 each time one of the filling tubes hereinafter referred to is brought to a position of rest beneath the lower or discharge end of the hopper. It may also be noted here that shaft 13 is driven from a shaft of the hereinafter described packing plunger assembly 7 so that tripping of scale 11 and the filling of the tube positioned beneath the hopper

12 is timed to occur when the packing plunger is travelling downwardly through a previously filled tube which has been advanced to the packing station at which the packing plunger is located.

The filling tube assembly and its operating means

This assembly in the particular construction illustrated includes a plurality of equi-distant filling tubes 15 depending, in circular series, from a turn-table 16 carried by the upper portion of

a sleeve 17 which is mounted to turn about a stationary vertical shaft 18. A horizontal gear wheel 19 is fixed to turn with the table 16 and sleeve 17. This gear wheel 19 is driven by a pinion 20 carried by the lower end of a vertical

40 shaft 21 which is journaled in upper and lower bearings 22 carried by the platform 23 of the frame structure generally indicated at 24. Shaft 21 is driven through bevel gears 25 and 26 by a horizontal counter shaft 27 which is also journaled in bearings 28 carried by platform 23. Shaft 27 is equipped with an electromagnetic brake 29 and is connected to the main drive shaft

30 by a releasable drive connection including sprocket 31, sprocket chain 32, sprocket 33 and 45 an electromagnetic clutch 34. This drive connec-

tion between shafts 27 and 30 is operative when clutch 34 is engaged and is inoperative when said clutch is deenergized and disengaged.

The filling tubes 15 in the particular construction illustrated by way of example are of oblong rectangular cross section and are open at both ends. The lower half of each tube includes a movable half section 35 whose side flanges 37 are slidably fitted between the side flanges 38 of the opposing fixed half section 39. The section 36 is normally held in the inwardly swung position shown in Figs. 1 and 2 by a spring hinge 40 located at the upper end thereof. In this normal position of tube section 36, the lower end of the tube is restricted and given a tapered configuration which makes it easier to slip a bag or package thereon as indicated at X in Fig. 1. Stops 42, Fig. 2, carried by the flanges 37 of each tube section 36, are fitted in slots 43 provided in extended portions of the overlapping flanges 38. These stops permit a limited outward movement of the tube section 36 relative to the opposing section 39 when the packing plunger is moved downwardly through the tube as subsequently described in connection with the packing operation. The bag or package X which is fitted on the lower end of the tube 15 is frictionally held in place thereon by suitable outwardly bowed spring strips 45.

The turn-table 16 is intermittently operated, being in the particular machine illustrated, turned through one-quarter of a complete revolution each time the clutch 34 is engaged to establish a drive connection between the table driving shaft 27 and the main shaft 30. After the table has travelled through this distance the clutch 34 is automatically disengaged and the brake 29 is simultaneously set to bring the table to a stop and to hold it stationary until the clutch 34 is re-engaged. As the table 16 is brought to rest at the end of each quarter revolution one of the tubes 15, to which a bag or package X has previously been applied, is positioned directly beneath the lower or discharge end of the hopper 12 and the diametrically opposite tube is brought to a bag receiving position in front of the hopper and is fitted with a bag or package by an attendant stationed in front of the machine. As each bag carrying tube 15 comes to rest beneath the hopper 12 at what may be termed the filling or loading station, the scale 11 is tripped by automatic operation of the tripping shaft 13 so that a measured charge of the material to be packaged is deposited in the tube and drops down upon the bottom of the tube-carried bag or container. When this filling operation is completed the clutch 34 is automatically re-engaged to rotate the table through another quarter of a revolution during which the filled tube moves on to the packing station represented by the plunger assembly 7 and the packing form assembly 8. It will thus be seen that, as each tube 15 is moved through a complete circle by intermittent operation of the table 16 it travels from a bag receiving station located forwardly of the hopper 12 to a filling or loading station where it is positioned directly beneath the hopper 12; from thence to a packaging station represented by the packing plunger assembly 7 and the packing form assembly 8 and from thence back to the bag receiving station. At the packing station a packing plunger, hereinafter referred to, causes the material and package to be forced from the tube into an underlying packing form where the pressure of the plunger serves to pack the ma-

terial tightly in the package or bag while the side and bottom walls of the same are sustained against the plunger pressure by the corresponding walls of the packing form.

5 *The packing plunger assembly and its operating means*

This assembly includes a cylindrical plunger 41 which slides vertically in a sleeve bearing 48 carried by the platform 23 and is equipped, at its lower end, with an oblong packing head 49, which may be rectangular or other suitable shape to fit into the package X. The upper end of plunger 41 is fastened to a guide carriage 50 which, in turn, is suspended from a supporting shaft 51 by a connecting rod 52, see also Figs. 3 and 4. The shaft 51 extends between and is rigidly secured, by fastening pins 53 to diametrically opposite carrying portions of two endless sprocket chains indicated at 54 and 55. The chain 54 is trained around upper and lower chain sprockets 56 and 57 carried by the inner ends of short tube shafts 58 and 59 journalled in bearings 60 and 61 carried by one side of the plunger guide frame generally indicated at 62. The sprocket chain 55 is trained around upper and lower sprockets 63 and 64 carried by the inner ends of short stub shafts 65 and 66 journalled in bearings 67 and 68 carried by the opposite sides of the plunger guiding frame 62. The front and rear portions 62a and 62b of frame 62 serve as guide tracks for front and rear guide rollers 71 and 72 journalled in the plunger guide carriage.

The stub shaft 58 of the plunger driving chain 54 drives the trip shaft 13 of scale 11 through a drive connection comprising sprocket 74, sprocket chain 75 and sprocket 76, Fig. 1. It is this last mentioned drive connection which times the tripping of the scale 11 so that one tube 15 is being filled while the material and bag carried by another tube is being forced into one of the packing forms by the downward movement of the packing plunger 41.

The lower stub shafts 59 and 66 of the plunger driving chains 54 and 55 are driven from the main drive shaft 38 through a releasable drive connection comprising reduction gearing 78a, shaft 78b, sprocket wheel 78, sprocket chain 79, sprocket wheel 80 and electromagnetic clutch 81. Shaft 78b is equipped with an electromagnetic brake 78d, Fig. 1. The operation of the clutches 34 and 81 is controlled by suitable switches hereinafter referred to so that the clutch 81 is disengaged when the clutch 34 is engaged and vice versa. The clutch 81 is disengaged each time the plunger 41 is raised to its starting position after it has made a downward or working stroke. The plunger 41 is caused to make this working stroke and to return to its starting position by automatic engagement of clutch 81 which occurs simultaneously with the disengagement of clutch 34 to permit the turn-table 16 of the filling tube to be brought to rest with one tube 15 positioned beneath the hopper 12 and a previously filled tube 15 positioned to permit the plunger 41 to be passed downwardly therethrough, said last mentioned tube being located directly over one of the packing forms of the packing form assembly 8 so that the movement of the plunger downwardly through said tube causes the material and the bag carried by the tube to be forced into the underlying packing form. Any other means for actuating the plunger 41 may, of course, be employed, if desired.

The packing form assembly and its operating means

This assembly includes a turn-table 85 carried by a tube 86 mounted to turn around a stationary shaft 87. The rotary movement of table 85 is synchronized with the rotary movement of the previously mentioned tube-carrying table 16 in any suitable manner, for example, by a drive connection comprising a sprocket chain 87a trained around sprockets 88 and 89 carried, respectively, by the tubes 17 and 86. The turn-table 85 carries a plurality of bag receiving packing forms 91, see Figs. 1, 7 and 8, arranged in circular series thereon, each form including a vertically movable horizontal bottom wall 97 and four vertically extending marginal walls 98, 99, 100 and 101. For convenient description the marginal walls 98, and 101 of each form are herein-after referred to as the front and rear walls while the remaining walls 99 and 100 are herein-after referred to as the side walls.

The lower ends of the front wall 98 and the side walls 99 and 100 are hingedly connected to the table 85 as indicated at 102 so that these walls may be swung outwardly from a truly vertical form contracting position to a vertically inclined form expanding position and vice versa. The rear wall 101 of each form is rigidly attached to table 85 so that this wall always remains in a position perpendicular to the upper surface of the table. It will also be noted that the rear wall preferably 101 comprises two sections 103 and 104, Fig. 8, arranged in side by side arrangement with the inner edges spaced apart to provide an intervening slot for the passage of a lifting arm 107 which carries the bottom wall 97 and is free to slide on a vertical guide post 108. The several guide posts 108 have their lower ends rigidly secured to the table 85 and their upper ends interconnected by a rectangular bracing frame 109 which is open at the center to permit passage of the shaft 87 therethrough. The bottom wall lifting arm 107 of each form is connected to the bottom wall lifting arm 107 of the diametrically opposite form by a flexible element 110 which is trained around guide pulleys 111 carried by brackets 112 mounted at diametrically opposite corner portions of the rectangular bracing frame 109. It will thus be seen that when the bottom wall 97 of one packing form 91 is moved downwardly by the packing plunger, the connected bottom wall of the diametrically opposite form will be caused to move upwardly. Any other connections between the bottom walls of a pair of packing forms may be employed, if desired.

The contraction and expansion of each form 91 may be controlled in any suitable or desired manner, and in the construction illustrated, this is effected by a vertically movable form encircling member or plate 114 provided with a rectangular central opening 115 through which the marginal walls of the form extend. This plate slides on guide rods 116 and is provided with depending guide tubes 117 encircling said rods. Coil springs 118 arranged on the lower portions of guide rods 116 act upwardly against the lower ends of the guide tubes 117 and normally serve to hold the plate 114 in an elevated position as indicated by the showing of the left hand form in Figs. 1 and 7. The front wall 98 and the side walls 99 and 100 of each form are each provided with a cam projection 120 secured to the outer side thereof and are adapted to cooperate with the plate 114. As here shown each cam projection 120 consists of a vertically extending angle iron

section having its upper end tapered to provide an inclined portion 121. When the plate 114 associated with each form 91 is depressed, as hereinafter described, to the lowered position represented by the showing of the right hand form in Figs. 1 and 7, the front and side edges of the plate opening 115 act against the inclined edges 121 of the cam projection 120 to swing the front and side walls 98, 99 and 100 of the form inwardly to an upright or form contracting position. As each form 91 is moved around to the right hand side of shaft 87, the plate 114 thereof is depressed by means of a roller 123 carried by a stationary arm 124 fixed to and extending outwardly from the shaft 87. In this connection it will be noted that the roller 123 rides upon and depresses a curved cam track member 125 mounted on the upper surface of plate 114 adjacent the rear edge thereof, said cam track member 125 being curved about a center coinciding with the central axis of shaft 87 and being provided with tapered end portions 126. When the cam track 125 passes out of engagement with the roller 123 the plate 114 is returned to its normal elevated position by the springs 118 and permits the walls 98, 99 and 100 of the form to be moved outwardly to a vertically inclined position or form expanding position, for example, any other means for contracting and expanding the packing forms in timed relation to the operation of the machine may be employed.

The form carrying table 85, being driven from the tube carrying table 16 by the drive chain 87a, is turned through a part of a revolution each time the electromagnetic clutch 34 is engaged, for example, a quarter of a revolution in the construction illustrated. At each quarter revolution of table 85 one of the forms 91 is positioned directly below the packing head 49 of the plunger 47. At the same time, owing to the concurrent rotation of the form carrying table 85, one of the filling tubes 15 is interposed between the elevated plunger head 49 and the underlying form 91. As the tables 16 and 85 come to rest the plunger head 49 is moved downwardly through the aligned tube 15 and causes the material and the bag carried by said tube to be forced into the underlying form. At this time the bottom wall 97 of the form into which the material and the bag is forced by the plunger is in its elevated position at the top of said form. However, as the plunger descends the underlying bottom wall 97 is caused to travel downwardly to the bottom of the form and, in so doing, causes the connected bottom wall 97 of the diametrically opposite form to be raised to its elevated position. In this connection it will be understood that, as each form arrives at its plunger receiving position, the front and side walls thereof are operated to a form contracting position and are held in this position until the packing operation is complete and the plunger is moved upwardly on its working stroke. As the plunger packing head 49 enters the receiving form it compresses the material against the bottom and sides of the bag while these portions of the bag are sustained against such pressure by the marginal and bottom walls of the form. As previously stated the plunger 47 is driven so that, at each operation thereof, it makes a full working stroke and then returns to its elevated or starting position. As the plunger returns to its starting position a projection 130, carried by the portion of the plunger supporting the connecting rod 52, engages and closes a normally open switch 131 located at the upper end

of the plunger guide frame 62, Figs. 3 and 4. The switch 131 energizes the right hand clutch magnet 132 shown in Fig. 6 and draws the magnetic core or solenoid 133 to the right. The solenoid 133 carries a clutch shifting yoke 134 which is engaged in the groove 135 of a clutch sleeve 136 which is rigidly connected to the movable clutch members 137 and 138 of the electromagnetic clutches 34 and 81. Consequently, as the solenoid core 133 is drawn to the right by energization of the magnet 132 it causes the clutch 34 to be engaged and the clutch 81 to be disengaged. This disrupts the drive connection between the main drive shaft 30 and the plunger 47 and establishes a drive connection between said main drive shaft 15 and the tube carrying table 16 through the medium of the sprocket chain 32 and other parts which have been described. The plunger 47 is thus brought to rest in its elevated position while the tables 16 and 85 are rotated through another quarter of a revolution, during which the filling tube 15 and the form 81 previously positioned beneath the plunger 47 are replaced by another form and another filled bag carrying tube. As each form 81 travels beyond its plunger receiving or packing station the front and side walls thereof are permitted to swing outwardly by upward movement of the plate 114 to facilitate removal of the packed bag from the form when it has so moved around the shaft 87 to a position diametrically opposite the plunger receiving position or packing station.

As each form carrying a packed bag reaches a position diametrically opposite the packing station the bottom wall thereof is raised by the downward movement of the bottom wall of the diametrically opposite form which is being depressed by the descending motion of the plunger in a subsequent packing operation. As the bottom wall of each packed form is raised to the top of the form it moves the bag upwardly to a position where it can be conveniently discharged onto a suitable conveyor (not shown) by a mechanically actuated means such, for example, as a pusher plate 141. This pusher plate is carried 40 by an arm 142, Fig. 7, which slides in a guide 143 rigidly mounted on the shaft 87. A link or pitman 143a is pivotally connected to the arm 142 and a sprocket 144 which is driven by a chain 145 from a sprocket 146 mounted on a shaft 147. The last mentioned shaft is driven by gearing (not shown) from a shaft 148 which, in turn, is driven from the shaft 78 of the plunger operating chain 54 through a drive connection comprising sprocket 149, sprocket chain 150 and sprocket 151.

The herein described mechanism for operating the pusher plate 141 is arranged so that the pusher plate is drawn inwardly toward the shaft 87 during the downward movement of plunger 47 and is moved outwardly with relation to such shaft during the upward or return movement of the plunger. During the outward movement thereof the pusher plate engages the bag carried by the elevated bottom wall of the adjacent form and pushes said bag onto the previously mentioned conveyor.

Each time the tube carrying table 16 is rotated through one-quarter of a revolution one of a plurality of arms 155 carried by said table engages and closes a normally open switch 156 mounted on a supporting standard 157 of the platform 23. The closure of switch 156 energizes the left hand clutch magnet 158 (Fig. 6) and causes the solenoid 133 to be moved to the left,

thus releasing the clutch 34 and engaging the clutch 81. This disrupts the drive connection previously established between the main drive shaft 30 and the tube carrying table 16 and re-establishes the drive connection between the said main shaft and the shaft 86 of the plunger operating mechanism whereby said plunger is again moved downwardly on its return stroke and then returned to its normal or elevated position.

The movable elements of the previously mentioned electromagnetic brakes 29 and 18d are connected by yokes 162 and 163 to end portions of the clutch operating solenoid 133. Fig. 6, by any suitable means (not shown), so that when the clutch 34 is disengaged, the brake 29 is simultaneously applied to stop the table 16, and when the clutch 81 is disengaged, the brake 18d is applied to stop the plunger actuating mechanism. By reason of these connections the brake 29 is engaged simultaneously with the disengagement of the clutch 34 and is disengaged simultaneously with engagement of said clutch. Similarly the brake 18d is engaged when the clutch 81 is disengaged and is disengaged when said clutch 81 is engaged. These brakes 29 and 18d serve, as previously described, to bring the table 16 and the plunger 47 quickly to rest when the drive connection between these last mentioned parts and the main drive shaft 30 is disrupted by disengagement of the controlling electromagnetic clutches.

The drive shaft 30 rotates continuously when the machine is in operation and is provided with a pulley 30a adapted to be belt connected to the drive pulley by a motor or other prime mover.

In Figs. 9 and 10 I have shown a modified arrangement for operating the pusher plate 141. In this case the pusher plate is provided with a guide stem 168 which slides in guides 169 carried by a frame structure 170 which is fastened to shaft 87. The guide stem 168 is provided with a roller 171 which is fitted in a cam groove 172 formed by and between suitably shaped cam ribs 173 carried by a cylinder 174 which is fixed to a shaft 175 journalled in suitable bearings 176 carried by the frame structure 170. One end of shaft 175 is provided with a sprocket wheel 177 adapted to be driven by a chain such, for example, as the chain 145 shown in Fig. 1.

The cam groove 172 is shaped so that the pusher plate 141 will be advanced and retracted in suitably timed relation to the rotation of the form carrying table 85.

Any other means may be employed for removing the packages from the machines.

The apparatus described has the advantages of being of simple and efficient construction and of being capable of compressing the material to any desired extent, even if the package is in the form of a bag of relatively thin paper, since the package is securely confined against rupture during packing or compressing of the material by the walls of the packing forms. After the material has been compressed to the desired extent, the walls of the packing forms are moved outwardly to release the package, so that damage to the package in discharging the same from the machine is also avoided.

I claim as my invention:

1. In a packaging machine, the combination of a rotary turn-table having a plurality of packing forms mounted thereon and movable intermittently to position the packing forms successively in a package receiving position, means for placing packages into the packing forms and

compressing the contents thereof while in said forms, said forms having movable bottoms which are moved downwardly when the packages are inserted in said forms, and a mechanical connection between the bottoms of a pair of forms for moving the bottom of one form upwardly when the bottom of another form is moved downwardly during compression of the contents of a package contained therein.

2. In a packaging machine, the combination of a rotary turn-table having a plurality of packing forms mounted thereon and movable intermittently to position the packing forms successively in a package receiving position, means for placing packages into the packing forms and compressing the contents thereof while in said forms, said forms having movable bottoms which are moved downwardly when the packages are inserted in said forms, and a flexible cord connecting the bottoms of two packing forms to produce upward movement of the bottom of one packing form when the bottom of the other packing form is moved downwardly.

3. In a packaging machine, the combination of a rotary turn-table having a plurality of packing forms mounted thereon and movable intermittently to position the packing forms successively in a package receiving position, a plunger for moving a package downwardly in a packing form and compressing the contents thereof in said form, said packing forms having movable bottoms, and means connecting the bottoms of each pair of packaging forms for raising the bottom of one form of a pair for ejecting a package therefrom when the bottom of the other form is moved down by said plunger while compressing the contents thereof.

4. In a packaging machine, the combination of a rotary turn-table having a plurality of packing forms mounted thereon and movable intermittently to position the packing forms successively in a package receiving position, means for placing packages into the packing forms and compressing the contents thereof by downward pressure while in said forms, said forms having movable bottoms which are moved downwardly when the packages are inserted in said forms, and compressed therein, and connections between the bottoms of each pair of said packing forms for moving said bottom of one form upwardly to discharge a package therefrom when the bottom of the other form of the pair is moved downwardly, and means for moving said packages laterally from the raised bottoms to remove them from said turn-table.

5. In a packaging machine, the combination of a turn-table having a plurality of packing forms mounted thereon and movable intermittently to place said packing forms successively into package receiving and compressing positions, means for feeding the packages into positions above said forms, a plunger for entering the open upper ends of said packages and moving the packages into said forms while compressing the contents thereof, means actuated by said plunger through the medium of the contents of one of said packages while compressing the same, for moving a package upwardly out of another packing form, and means actuated in timed relation to the movement of said plunger for pushing the packages sideways from said turn-table.

6. In a packaging machine, the combination of a turn-table having a plurality of packing forms mounted thereon and movable intermittently to move the packing forms successively into and

out of package receiving position, said forms having side walls movable toward each other into operative positions to confine the side walls of a package while the contents of the same are compressed, and into inoperative positions to release the side walls of said package to facilitate discharging of the package, a member movable lengthwise of said walls for moving the same into their package confining positions, and cam means on said member for moving the same into a position to move the walls of a packing form toward each other when said packing form moves into package receiving position.

7. In a packaging machine, the combination of a packing form adapted to receive a package containing material, and a plunger which compresses the contents of said package while the same is in said form, said form including side walls hinged at one end to swing into positions to contract said form and into other positions to expand said form, cam faces on the outer surfaces of said hinged side walls, a form encircling member extending about the walls of said form and engaging said cam faces during up and down movement thereof to move said hinged walls into their operative positions, means for guiding said encircling member for movement relatively to said form, and means for imparting movement to said encircling member in directions to move said hinged walls into form contracting position and to release said hinged walls to permit expansion of said form.

8. In a packaging machine, the combination of a turn-table having a plurality of packing forms mounted thereon and movable intermittently to move the packing forms successively into and out of package receiving position, said forms having side walls pivoted at their lower ends and having the parts thereof above said pivots, movable toward each other into operative positions to confine the side walls of a package while the contents of the same are compressed, and into inoperative positions to release the side walls of said package to facilitate discharging of the package, said packing forms having movable bottom walls which are movable downwardly when a package is inserted into a packing form and which are movable upwardly to eject the package from the form when said side walls are in their package releasing positions, and connections between the bottom walls of two packing forms to raise one bottom wall when the other bottom wall is moved downwardly.

9. In a packaging machine, the combination of a packing form adapted to receive a package containing material, and a plunger which compresses the contents of said package while the same is in said form, said form including side walls hinged at one end to swing into positions to contract said form and into other positions to expand said form, cam faces on the outer surfaces of said hinged side walls, a form encircling member extending about the walls of said form and engaging said cam faces during up and down movement of said member to move said hinged walls into their operative positions, means for guiding said encircling member for movement relatively to said form, means for imparting movement to said encircling member in directions to move said hinged walls into form contracting position and to release said hinged walls to permit expansion of said form, and means for pushing the packages laterally from the bottom walls when the same are in raised position, to remove the packages from the turn-table.

11

10. In a packaging machine, the combination of a plurality of filling tubes, means on said tubes to engage packages to releasably attach the same to the lower open ends thereof, a rotary turn-table on which said tubes are mounted and which moves said tubes intermittently to various stations in a circular path, means at one of the stations of said tubes for introducing measured charges of material into said tubes while the lower ends thereof are closed by said packages, a second rotary turn-table having a plurality of packing forms arranged thereon and movable intermittently simultaneously with said first mentioned turn-table about an axis substantially parallel with the axis of said first turn-table, 15 said packing forms having side walls movable toward and from each other to confine and release a package, means for synchronizing the movement of said turn-tables to position a packing form under a filling tube and package, a plunger slidably mounted on said machine and arranged to enter a filling tube when over a packing form to move the package and material from the filling tube to the packing form and to compress and pack the material in said package while the same is in said form, means for moving said side walls of a form toward each other prior to the entry of said plunger into the same and for releasing said side walls to permit the articles to be ejected therefrom when said plunger is withdrawn therefrom, and means which alternately actuate said turn-tables and said plunger.

11. In a packaging machine, the combination of a plurality of filling tubes, means on said tubes to engage packages to releasably attach the same to the lower open ends thereof, a carrier on which said tubes are mounted and which moves said tubes into positions to receive a quantity of material, a rotary turn-table having a plurality of packing forms arranged thereon and movable intermittently into positions in which a filling tube of said carrier is positioned over a packing form on said turn-table, each of said packing forms having a bottom which is movable upwardly and downwardly, a plunger movable into a filling tube when positioned over said packing form for stripping the package from said form and for moving the package and contents into the packing form disposed beneath the package, the movable bottom on said packing form being moved downwardly by said package when actuated by said plunger, and means actuated through the medium of said package for raising said

12

movable bottom of another package form to eject a package therefrom.

12. In a packaging machine, the combination of a plurality of filling tubes, means on said tubes to engage packages to releasably attach the same to the lower open ends thereof, a carrier on which said tubes are mounted and which moves said tubes into positions to receive a quantity of material, a rotary turn-table having a plurality of packing forms arranged thereon and movable intermittently into positions in which a filling tube of said carrier is positioned over a packing form on said turn-table, a plunger movable into a filling tube when positioned over said packing form for stripping the package from said form and for moving the package and contents into the packing form disposed beneath the package, said packing forms having bottoms movable up and down and which are moved downwardly by said package when actuated by said plunger, means connecting the bottoms of pairs of said packing forms for raising said movable bottom of one form to eject a package therefrom when the bottom of the other form of a pair is moved downwardly by said plunger while inserting a package into the other packing form of a pair.

JOHN W. McCASLIN.
